(No Model.)

T. McCROSSAN.

HEATER FOR CARS OR BUILDINGS.

No. 381,806.

Patented Apr. 24, 1888.

UNITED STATES PATENT OFFICE.

THOMAS McCROSSAN, OF WINNIPEG, MANITOBA, CANADA.

HEATER FOR CARS AND BUILDINGS.

SPECIFICATION forming part of Letters Patent No. 381,806, dated April 24, 1888.

Application filed October 15, 1887. Serial No. 252,436. (No model.) Patented in Canada June 6, 1887, No. 26,899.

To all whom it may concern:

Be it known that I, THOMAS McCROSSAN, of 5
Winnipeg, Manitoba, Canada, have invented a
new and useful Improvement in Heaters for
Cars and Buildings, (for which I have obtained
a patent in Canada, No. 26,899, bearing date
June 6, 1887,) of which the following is a specification.

My improvement belongs to the class of hot- 10
air heaters. It is more particularly designed
and adapted for use in railway-cars, although
applicable for heating dwellings and public
buildings as well. The fire-box is made of
cast-iron and inclosed by a shell or casing of
steel or wrought-iron, the two being separated
15 by an air space or chamber, into which cold
air is admitted, and from which it is discharged
in a heated condition. The draft is supplied
through the hollow door, the construction and
20 arrangement being such that the slides for con-
trolling the draft serve also as means for fast-
ening the door. A movable plate or disk is
also provided for automatically closing the
smoke-exit. The details of construction, com-
25 bination, and operation of parts are as here-
inafter described.

In the accompanying drawings, Figure 1 is
a central vertical longitudinal section of my
heater. Fig. 2 is a central vertical transverse
30 section of the heater. Fig. 3 is a horizontal
section on line $x-x$, Fig. 1. Fig. 4 is a plan
view of the perforated diaphragm detached.
Fig. 5 is a section of the diaphragm on line $y-y$,
Fig. 4. Fig. 6 is a perspective view of the
35 door detached.

A indicates the cast iron fire-box, and B the
steel or wrought-iron casing or shell. The fire-
box A is contained within the casing B and
separated from it by an air-space at all points—
40 that is to say, on the top, bottom, sides, and
ends. Suitable braces are interposed between
the fire-box and casing for the purpose of hold-
ing them rigidly separated yet connected. The
fire-box A is secured to the bottom of the casing
45 by means of iron rods; but for this purpose va-
rious other means may obviously be employed.
I provide the casing B with a series of hori-
zontal diaphragms, C, thus dividing its inter-
ior into two chambers, in the lower one of
50 which the fire-box A is contained. These dia-
phragms have non-registering openings a' , cor-
responding to the openings a in the bottom of

the casing B. (See Fig. 2.) The smoke-pipe
c, attached to fire box A, passes longitudinally
through the upper chamber and joins a verti- 55
cal flue, c', above the top of the casing. In
the said top are also openings a' , surrounded
by circular flanges and provided with valves
for regulating the exit of the heated air into
the apartment in which the heater is located 60
or the passage of such air into flues for con-
ducting it to other apartments—that is to say,
comparatively cold air is admitted through
bottom openings, a , becomes heated in the
space surrounding the fire-box A, then passes 65
through openings a' into the upper chamber,
and finally discharges through the top open-
ings, a' .

A special and important feature of my in- 70
vention is the construction of the door d and
the means for securing or fastening it. The
door is hollow, and has an opening, 1, in its up-
per end, and another, 2, in its inner side near
the bottom. The purpose of these openings
is to enable air to be supplied to the fire-box 75
A through the bottom openings, a , for sup-
porting combustion without requiring any
exterior draft-opening through the door, which
would endanger the safety of the car in case
of overturning. 80

To wholly or partly close the draft opening
1, I employ slides or dampers e—that is to
say, the said slides work horizontally across
the top of the door in lips or flanges that serve
as guides, Fig. 6, and are operated by rods e', 85
that work through holes in the sides of the
casing B and in the jambs of the door.

The slides never require to be wholly with-
drawn from the guides, save when the door is
to be opened; and hence it will be seen that in 90
addition to their ordinary or normal function
the slides e serve also as means for securing or
locking the door d, so that accidental opening
of the latter in the case of accident—as when
the stove is overturned—is impossible; and
hence the burning contents of the fire-box A
will not be discharged through the door-open-
ing, so as to further endanger the safety of the
car and passengers. To similarly prevent the
contents of the fire-box A from escaping into 95
the smoke-pipe in case of overturning of the
car, I provide an automatically-closing valve,
f, Figs. 1 and 2, which consists of an iron disk
suspended by bolts that pass loosely through

holes in the top of the fire-box around the pipe-collar or smoke-exit. This disk being larger than the collar or exit and the bolts being free to move vertically, it will operate by gravity 5 when the car overturns, and thus close the exit against escape of the burning fuel, cinders, &c.

On each side of the fire-box A, below the plane of its bottom and longitudinally above the air-inlets *a*, is located a metal pan, *g*, constituting a receptacle for live coals and cinders in case the stove should be overturned and the fire-box broken by the shock, so as to spill its contents. In other words, these pans would prevent the contents of the fire-box from escaping 15 through the air-inlets *a*. Their inner edges are bent upward and then inward, to enable them to more effectually prevent escape of any burning fuel that they may chance to receive. Similar but inverted catch-pans, *g' g'*, are arranged 20 directly above the former, *g g*, and above the plane of the top of the fire-box, to receive the burning fuel in case the stove should be turned upside down.

The three-part diaphragm C serves as an additional means for preventing the coals passing out at the top of the stove. It will be seen that if the coals should pass through the openings *a* in the lower plate of said diaphragm they would be arrested by the other two; yet the said 25 openings allow free passage of heated air.

The single arrows indicate the direction of draft and products of combustion and the double arrows that of the heated air. In this

instance I have shown the fire-box and casing as rectangular in form; but I propose to make them cylindrical in some cases. 35

What I claim is—

1. The combination, with the stove proper and its surrounding casing, between which is an air-chamber, as specified, of the hollow door 40 which closes the registering openings in both said stove and casing and has itself an imperforate face and top and bottom air-openings, whereby, when the door is closed, air to support combustion is supplied through it from 45 the said interior chamber, as shown and described.

2. The combination, with the fire-box and casing therefor, of the hollow door having an inlet from the upper air-chamber and an outlet into the fire-box, and slides working 50 through the sides of the casing and in guides on the top of the door, whereby they are adapted for closing said inlet and also for fastening said door, as shown and described. 55

3. The combination, with the fire-box and a casing separated therefrom by an air-space and having air-inlets *a* in its base, of catch-pans *g*, having inwardly-bent edges and located in such space between the fire-box and inlets, 60 substantially as shown and described.

THOMAS McCROSSAN.
